UNITED STATES PATENT OFFICE.

DMITRY TROUBTSCHANINOFF, OF NEW YORK, N. Y.

SAFETY ATTACHMENT FOR SUBMARINE MINES.

1,292,542.

Specification of Letters Patent. Patented Jan. 28, 1919.

Application filed April 6, 1918. Serial No. 227,083.

To all whom it may concern:

Be it known that I, DMITRY TROUBTSCHANINOFF, citizen of Russia, and residing at New York, county of New York, State of New York, have invented certain new and useful Improvements in Safety Attachments for Submarine Mines, of which the following is a specification.

The present invention relates to improvements in submarine mines and particularly to a safety attachment for mines of this character which are intended to be maintained at a pre-determined depth below the surface of a body of water.

It frequently happens that such mines become detached or separated from the anchors provided for maintaining them at the desired depth and rise to the surface which is objectionable, both because of the danger of unintentional or accidental contact therewith of vessels or as indicating the probable location of a mine field to enemies.

The particular object of the present invention is to provide a safety attachment for such a mine whereby when the mine rises above a pre-determined depth water will be admitted thereto causing it to sink to the bottom.

In the accompanying drawing:

Figure 1, is a longitudinal sectional view showing an embodiment of the invention;

Fig. 2 is an outer end view;

Fig. 3 is a sectional view substantially on the line 3—3 of Fig. 1; and

Fig. 4 is a section on the line 4—4 of Fig. 1.

Referring to the drawings 1 indicates a portion of the shell or casing of a mine to which the safety appliance is attached. As shown the attachment comprises an externally threaded cylindrical body 2, which is engaged with suitable threads in the wall of a passage through the wall of the shell 1, preferably formed in a portion of greater thickness than the body of the casing.

At its outer end the threaded member 2 is provided with a head 3, which may be integral with or formed separately from the part 2 and which has a socket in its outer face; and said member 2 is provided with an inward cylindrical extension 4. Within the cylinder is secured, as by suitable threads, an end piece 5 provided with a suitable aperture for the firing pin support hereinafter referred to.

A cylinder 6 is arranged within the mem-

bers 2, 4, having at its outer end an annular flange 7, which contacts with the bottom wall of the socket at the outer end of the head 3. The inner end of the said cylinder 6 or an extension thereof, shown as of slightly less diameter, is adapted to extend into the central opening in the end closure 5 of the outer cylinder. As shown the flange 7, at the outer end of the cylinder is not formed integral with the body of the cylinder but as being carried by a sleeve which is formed separate from and connected by a thread with the cylinder 6. The inner end of said sleeve serves as an abutment for a coiled pressure spring which is arranged between the two cylindrical members and bears at its inner end against a tension adjusting nut 8.

The nut 8 engages threads formed in the inner face of the member 4, portions of said nut being exposed through slots 9 in said cylinder whereby the nut may be engaged as by a suitable spanner and turned to place the spring 10 under the desired amount of compression.

A flexible diaphragm 11 is arranged over the flange 7 and clamped in place adjacent its margin by a ring 12 and plug 13 which is screwed into the outer end of the socket in the head member 3. A water proof disk 85 may be arranged between the upper surface of the diaphragm and a disk 14 which is seated in the socket in the head 3, and secured by a suitable thread to an outward sleeve like projection 7a on the flange 7. A carrier 15 having an explosive cartridge is screwed into the outer end of the cylinder 6.

A firing pin 16 is adapted to reciprocate in the cylinder 6 under the pressure of a coiled spring 17, which is interposed between a head attached to the pin, and a shoulder or abutment 18 in the cylinder. Normally the firing pin is held in the retracted position shown and the spring 17 maintained under tension by the action of a trigger 19. 100 This trigger is pivoted at one end 20, to the cylinder 6 and its other end is adapted to lie close against the inner closed end of said cylinder and to extend therewith into the opening in the end plug 5 of the outer cylinder. A spring 21 acts to normally press the trigger into the position shown in Fig. 1 and assists in properly positioning the parts to cause the trigger to enter the opening in the member 5 when assembling the several parts 110 of the apparatus. The inner end of the firing pin is provided with an enlarged portion

having a beveled surface 22 which is adapted to contact with a corresponding surface on the trigger 19.

It will be seen that when the cylinder 6 is moved outwardly sufficient to carry the lower end of the trigger beyond the inner face of the end plug 5 the spring 17 may force the firing pin outwardly exploding the charge in the holder 15, the inclined surface 22 acting to move the trigger laterally about the pivot 20.

A locking pin 23 is arranged in the plug 13, closing the socket at the outer end of the head 3, and bears against the member 14 to normally prevent outward movement of the member 14 and cylinder 6 carrying the explosive holder 15. Outward movement of said pin is prevented by a safety pin 24, the eye of which is to be connected by a relatively fine wire with the anchor provided for the mine.

The locking pin 23 is rotatable in its mounting in the plug 13, so that in case of any relative rotary movement between the body of the mine and its anchor, said pin will freely turn so that the safety pin 24 will always be properly positioned relative to the mine and anchor to permit it to be disengaged when sufficient strain is exerted on the wire connecting it with the anchor. It will be understood that when the mine and anchor are first submerged, they are nested or relatively close together and that as they separate the anchor exerts a sufficient pull on the safety pin 24 to withdraw it and permit the locking pin 23 to be moved outwardly by the spring 26, thus releasing the cylinder 6. Said cylinder is however retained in its inmost position by the soluble packing below referred to, or if that is dissolved, by the pressure of the water.

The cavity or chamber formed within the plug 13 contains a body of a suitable material, for example sugar, which will be dissolved by the action of water, an inlet to said chamber being normally closed by a readily detachable strip or disk 25.

When a mine having a safety device such as that hereinbefore described is to be placed in the water the closure 25 is first removed. As the mine sinks the material in the chamber in the plug 13 is dissolved and the member 14, and explosive holder 15 are exposed to the pressure of the water.

Spring 10 is placed under a tension which will correspond to the pressure of the water at a pre-determined depth, say slightly less than the depth at which the mine is designed to be maintained.

If now the anchor cable is broken or for any other reason the mine becomes detached from its anchor, and rises, the hydrostatic pressure on the cylinder 6 and parts connected therewith will be reduced so that the spring 10 will act to move said parts

outwardly in the outer cylinder 4. This outward movement releases the trigger 19 and permits the spring 17 to force the firing pin against the explosive charge in the holder 15. Such charge, (for example T. N. M. A.) is of sufficient capacity to break the parts in close proximity thereto and afford access to the body of the mine of water which will quickly fill the mine and cause the same to sink to the bottom.

As shown, diametrically opposite pins 30, extend through the body of the cylinder 6, their outer ends being guided in short elliptical slots 31 formed in the outer guide 4 and the inner ends of said pins extending inwardly into the path of the enlarged head at the lower end of the firing pin. These pins 30 act to prevent rotation of the cylinder 6 and parts connected thereto relative to the guide, and also to limit outward movement of the firing pin in said cylinder. This latter function is of particular importance in handling the several parts when assembling the mechanism, as without some such means, there would be danger of the pin being ejected through the outer end of the cylinder and injuring the workmen.

Having thus described the invention what is claimed as new and desired to be secured by Letters Patent is:

1. The combination with a submarine mine, of an explosive charge connected with the mine and adapted when exploded to provide an entrance for water to the mine, a firing pin adapted to cooperate with said explosive charge, means controlled by hydrostatic pressure to which the mine is subjected for normally retaining the firing pin in inoperative position, means for releasing the firing pin when the hydrostatic pressure on the mine is reduced, and means for driving the pin against the explosive charge.

2. The combination with a submarine mine, of a cylindrical guide secured to a wall of the mine, a holder for an explosive charge supported by said guide, a spring pressed firing pin, means controlled by hydrostatic pressure for normally maintaining the firing pin in inoperative position, and means for automatically releasing the firing pin on a predetermined reduction in the hydrostatic pressure.

3. The combination with a submarine mine, of a cylindrical guide secured to a wall of the mine, a cylinder within said guide, a main spring arranged between the cylinder and guide, a holder for an explosive charge carried by the cylinder, a firing pin within the cylinder, means controlled by hydrostatic pressure for normally maintaining the cylinder in position to retain said spring under pressure, and means for propelling the firing pin against the explosive charge when the cylinder is moved by said spring.

4. The combination with a submarine mine, of an explosive charge connected with the mine and adapted when exploded to provide an entrance for water to the mine, a firing pin adapted to coöperate with the explosive charge, and means controlled by hydrostatic pressure for preventing relative movement between the firing pin and explosive charge when the mine is submerged to the desired depth, said means being automatically rendered inoperative on a reduction in the hydrostatic pressure to which the mine is exposed.
5. The combination with a submarine mine, of an explosive charge connected with the mine and adapted when exploded to provide an entrance for water to the mine, a firing pin adapted to coöperate with the explosive charge, means controlled by hydrostatic pressure for preventing relative movement between the firing pin and explosive charge when the mine is submerged to the desired depth, said means being automatically rendered inoperative on a reduction in the hydrostatic pressure to which the mine is exposed, and means for preventing relative movement between the firing pin and explosive charge when the mine is not submerged.
6. The combination with a submarine mine, of a cylindrical guide secured to a wall of the mine and provided with a socket in its outer end, a sleeve fitted in said guide and having at its outer end a holder for an explosive charge, a coil spring arranged between said cylinder and guide, means for varying the pressure exerted by said spring, a firing pin movable with the cylinder relative to said guide, and a secondary spring adapted to impel the firing pin against the explosive charge when the cylinder has moved a predetermined distance relative to said guide.
7. The combination with a submarine mine, of a cylindrical guide secured to a wall of the mine and extending into the body thereof, a cylinder arranged within
- said guide and provided at its outer end with a holder for an explosive charge, pressure means acting to move the cylinder outwardly relative to the guide, means for exposing the outer end of the cylinder to hydrostatic pressure, and means automatically exploding said charge when the cylinder is moved outwardly on a reduction in the hydrostatic pressure to which it is exposed.
8. The combination with a submarine mine, of a holder for an explosive charge supported by the body of the mine and movable outward relative thereto, a firing pin adapted to coöperate with said explosive, means controlled by hydrostatic pressure for retaining the explosive charge at the limit of its inward movement when the mine is properly connected to its anchor, and means for effecting relative movement between the explosive charge and firing pin to explode the charge on a predetermined reduction in the hydrostatic pressure to which the mine is exposed, for the purpose described.
9. The combination with a submarine mine, of a holder for an explosive charge supported by the body of the mine and movable outward relative thereto, a firing pin adapted to coöperate with said explosive, and movable therewith relative to the body of the mine, means controlled by hydrostatic pressure for retaining the explosive charge and firing pin immovable relative to the body of the mine when the mine is properly connected to its anchor, means for effecting simultaneous relative movement between the body of the mine and said explosive charge and firing pin when the hydrostatic pressure on the mine is reduced, and means for subsequently effecting further relative movement between said charge and pin to explode the charge, for the purpose described.
- In testimony whereof I affix my signature.

DMITRY TROUBTSCHANINOFF.
